THERMAL SWITCH AND THE LIKE

Joseph Schmidinger, New York, N. Y.

Application April 30, 1937, Serial No. 139,932

9 Claims. (Cl. 200—113)

This invention relates to thermally operated switches, relays and the like.

One object of the invention is a novel switch or relay of the above indicated character embodying a multiple turn resistance wire or coil, the expansion and contraction of which are utilized for operating contacts.

A further object of the invention is a switch of the above indicated character which is characterized by the powerful switch action obtained from the expansion and contraction of the multiple turn hot wire coil.

A further object of the invention is a switch or relay of the above indicated character wherein a very slight expansion or contraction of a thermo-responsive element is amplified to a large switch movement and particularly such a structure which is characterized by its simplicity of construction and minimum parts.

A further object of the invention is a novel thermal switch whose operation is not disturbed by external shocks or vibrations.

A further object is a switch of this character which may be operated with extremely small currents.

A further object of the invention is a switch of the above indicated character having snap action and a long life.

A further object of the invention is a novel thermal switch of the above indicated character having a delayed hot wire action.

A further object of the invention is a thermal switch of the above indicated character which is characterized by its small and compact size, its simplicity in construction, and the ease and economy with which it may be manufactured.

Further objects of the invention will herein-after appear.

For a better understanding of the invention, reference may be had to the accompanying drawings forming a part of this application wherein:

Fig. 1 is a side view of one embodiment of the thermal switch of this invention;

Fig. 2 is a plan view thereof;

Fig. 3 is a circuit diagram illustrating a use of the switch shown in Figs. 1 and 2;

Figs. 4, 5 and 6 are diagrammatic views showing modifications of the invention;

Fig. 7 is a diagrammatic view indicating roughly the operation of the strip in these modifications;

Fig. 8 is a view of a modified form of strip; and

Figs. 9, 10 and 11 show modified structures.

Referring to the drawings, the invention is

illustrated as embodied in a thermal switch which

is mounted upon a supporting frame or base 1 which may be either of insulating material or metallic. The switch or relay comprises a U-shaped member 2 having legs 3 and 4 and this U-shaped member is made of a strong resilient metal, as, for example, of spring steel wire. Each of the legs 3 and 4 is provided with an insulating sleeve 5 of glass, ceramic or any other suitable insulating material having sufficient strength for the purpose. A coil of very fine resistance wire 6 is wound around and bound about the sleeves 5, one end 7 of the wire being fastened and electrically connected with a terminal 8, and the other end 9 of the coil being electrically connected at 10 with the leg 4 of the U. The wire 15 coil 6 of fine resistance wire is wound under tension around the legs 3 and 4 of the U-member, while the legs 3 and 4 are sprung toward each other against the inherent spring tension therein, so that when the resistance wire coil 6 20 is heated and caused thereby to expand, the legs 3 and 4 are permitted to spring outwardly from each other to the extent permitted by the expanding coil. The resistance wire of the coil 6 25 may be of any of the conventional types found on the market and the number of turns depends upon the voltage applied, the size of the wire, etc. and this particular embodiment of coil is adaptable to be connected across a 110 volt circuit. The dotted position shown in Fig. 1 indicates the resiliency of the spring legs 3 and 4, 30 namely, the relative positions the legs 3 and 4 would assume if entirely free from the resistance wire coil 6.

A metallic strip 12 is welded or otherwise securely fastened at its ends to the legs 3 and 4 at points between the wire coil 6 and the base plate 1. In the particular embodiment shown in Fig. 1 this strip 12 is of uniform width and strength throughout and is welded or fastened 40 to the legs 3 and 4 in a manner to cause it to assume the bowed position indicated in Fig. 2 and corresponding to the room temperature of the coil 6. The strip 12 carries a contact 12' which co-operates with another contact member 45 13. The latter is mounted in an insulating sleeve 14 of glass or other suitable insulating material, and this sleeve or insulating support 14 is carried by an angle piece 15 which is firmly secured at one end to the sleeve and on its other end to 50 the leg 4 of the U-member, the angle support 15 being conveniently disposed just above the base-board 1. The contact 13 is electrically connected through the resistance 16 with a terminal 17.

The U-member 2 is mounted upon and sup-

55

ported by the base or frame 1 at a single point of support and in the particular embodiment shown in Figs. 1 and 2 this single point of support is the lower end of the leg 4. The whole 5 thermal mechanism, including the U-member 2, the strip 12, contact 13 and the resistance coil 6 is thereby rendered immune in its operation to strains, distortion and warping of the frame or support 1. It is also less likely to be disturbed 10 by external shocks and vibrations. The end of the leg 4 is electrically connected with a third terminal 18.

In Fig. 3 is illustrated diagrammatically one of the many uses to which the thermal switch of Figs. 1 and 2 may be adapted. Here it is used 15 as a delayed hot wire relay switch for protecting an incandescent filament lamp 20 against excessive voltages and currents. This incandescent lamp is indicated as connected in circuit with devices 21, which upon the initial closure of the switch 22 permit an excessive voltage to be applied to and excessive current to flow through 20 the filament incandescent lamp 20. These devices 21 may represent radio tubes, for example. 25 The thermal switch functions to cut out a protective resistance 16 which is connected in shunt to the incandescent lamp 20 at the initial closing of the switch 22. Thus, with the resistance coil 6 connected across the circuit as indicated and 30 with the control switch 22 open, the bowed strip 12 connects in circuit the shunt resistance 16. Upon the closure, however, of the switch 22, the resistance coil 6 heats up and is caused to expand which permits the resilient spring legs 3 and 4 35 of the U-member to straighten out the strip 12 sufficiently to break the shunt resistance circuit. Before this interruption takes place, the devices 21 reach the operating condition wherein only the normal voltage and currents are supplied to 40 the incandescent lamp 20. A resistance 24 is shown connected in series with the devices 21 and the lamp 20. The resistance coil 6 may remain in the circuit as long as the devices 21 are operated, and due to the multiple turn and high 45 resistance of coil 6 only the infinitesimal current mentioned above is consumed. The resistance 16, of course, is properly proportioned with respect to the resistance 24 and other elements of the 50 circuit connected across the line 19 in order to prevent excessive current passing through the incandescent lamp 20.

In Figs. 4 to 6 I have illustrated the device 55 of my invention adapted to give a definite and strong snap action. The strip 30 here corresponds to the strip 12 of Figs. 1 to 3 and like strip 12 is firmly fastened or welded at its ends to the legs 3 and 4 of the U in a manner to cause the strip to be bowed and buckled as shown. The strip 30 is observed to have a reverse curvature, 60 comprising the two concave parts 32 looking upwardly at the drawing and the central convex part 31. The central part 31 carries a contact 12' which in one position engages the stop or contact 33 and in another position engages the contact or stop 34. In the cold position the contact 32 engages the contact or stop 33 and in the hot position the contact 32 engages the stationary contact or stop 34.

Fig. 7 shows diagrammatically approximate 70 positions assumed by the strip 30 in the normal operation. The full line position indicates the strip 30 in the position where the contact 32 engages the stationary contact or stop 33 which corresponds to the room temperature position of 75 the switch. The dotted line position indicates

roughly the position of the strip 30 with the contact 32 in engagement with the stationary contact or stop 34, which corresponds to the heated position of the switch and the maximum permitted separation of the ends of the legs 3 and 4. The parts 32 of the strip 30, during the heating of the coil 6 and the springing apart of the legs 3 and 4, are gradually flattened out with increasing radii of their curvatures to permit the snapping of the intermediate part of the strip past the dead center from the contact or stop 33 to the contact or stop 34. The dot and dash position indicates an intermediate position assumed by the parts 32 of the strip 30 when the resistance coil 6 is being cooled and the legs 3 and 4 are being drawn towards each other by the contracting coil. Here it is observed that the parts 32 of the strip are first caused to be bowed upwardly with curvatures having decreased radii, and this upward bowing of the parts 32 20 ultimately causes the reverse curved part 31 to snap downwardly against the contact or stop 33.

Figs. 4 to 7 show, as indicated above, one way of bowing and constraining the strip 30 to obtain the snap action. This may be effected by 25 upsetting the intermediate portion 31 of the strip 30 from the full bowed and constrained position shown in dotted lines in Fig. 4 to a position where it is prevented from returning to the dotted position under the room temperature condition 30 of the coil 6. This intermediate part 31 thus constrained occupies the position below the dead center or unstable position and is thus held therein until the coil 6 is reheated. Upon the heating of the latter, the intermediate part tends 35 to snap back across the dead center into the position indicated in dotted lines, but a contact or stop 34 is positioned below the dotted line position to arrest the strip before the reverse curvature 31 is eliminated. With the intermediate 40 part 31, therefor, of the strip resting against the contact or stop 34 which corresponds to the heated condition of the switch, the intermediate 45 part 31 may be caused to snap back to a position in engagement with the contact or stop 33 by interrupting the circuit through the coil 6 and cooling the same. During the cooling operation the ends of the strip 30 are brought 50 closer to each other and the effect of this compression is the tendency of the central portion 31 of the strip to at first bear more tightly against the stop or contact 34. As the cooling and contracting progress, however, with the stop or contact 34 preventing further upward movement 55 of the central portion 31, the additional compression results in the buckling of the end portions of the strip as shown in Fig. 7 which finally causes the intermediate portion 31 to break down by a snap action and assume a position against the lower stop or contact 33. It is observed that the first movement of the bowed parts 32 of the strip 30 is in one direction (downwardly) when the coil 6 is being heated and in the opposite direction (upwardly) when coil 6 is being cooled. 60 In the modifications Figs. 4 to 7 the strip 30 may be either of the uniform dimensions and strength as shown in Figs. 1 and 2, or it may have its intermediate portions weakened as shown in Fig. 8, but the construction in Fig. 8 is preferred where the snap action is desired. As 65 shown in Fig. 8, the strip 30 may be of uniform thickness throughout and the intermediate portions weakened by progressively narrowing the strip 30 from the ends towards the center where 70 75

in the particular embodiment shown the contact 12' is mounted. The weakening of the intermediate portions of the strip 30, as indicated, facilitates the snapping function, namely, the ability of the strip 30 to snap from one equilibrium position to the other. The strengthened ends 35 of the strip 30 also facilitates the welding or fastening of the strip to the legs 3 and 4 of the U to obtain the desired bias of the strip, which constantly tends to bring the strip into one predetermined position of equilibrium. The mounting is also facilitated. It is understood that while the contact 12' is disposed substantially at the center of the strip 30 which is rigidly fastened and constrained at both ends, it may be positioned at any other convenient position of the strip 30 which moves through an amplitude sufficient to control contacts. It is also understood that while the preferred construction is that shown in Fig. 8, the weakest portion of the strip may be at some other position than that at the middle point and the weakening may take any other form than that illustrated.

In Fig. 7 the relative positions of the legs 3 and 4 of the U-member are illustrated at the three different operating conditions and this is correct whether the U-member 2 is mounted and supported at a single point by fastening the end of one of the legs to the base 1, or whether it is mounted by fastening the same to the base 1 from any other single point, as for example by mounting it at a point on the cross member bridging legs 3 and 4.

In the circuit of Fig. 4 the thermal switch 35 functions as a relay, with the resistance coil 6 and terminals 40 and 41 connected across any suitable supply circuit together with any control switch for cutting in and out the coil. When the coil is out of circuit the controlled circuit is completed through 42 and 43, and when the coil 6 is in circuit to heat the coil 6 the circuit controlled is from 42 to 44.

In the circuit of Fig. 6 the strip 30 and the controlling contact 34 are connected in shunt with the coil 6 and, accordingly, when the circuit is completed through contacts 45 and 46 the resistance coil 6 is in circuit but is automatically shunted when it heats up and causes the strip 30 to snap over into engagement with the contact 34. The member 33 here serves as a stop. Thus, as long as the terminals 45 and 46 are connected across a supply circuit, the resistance 6 is automatically cut in and out successively.

In Fig. 5 there is also shown a flashing circuit, but in this case the coil 6 is connected in series with the circuit. When room temperature is reached the circuit is completed at the contact 33 but, upon heating up, due to the passage of current through the coil 6, the strip 30 is caused to snap over into engagement with the stop 34 to interrupt the circuit; but as soon as the room temperature is approached or reached, the circuit is again completed with the snap action at the contact 33.

While I have shown the coil 6 as being directly heated by the passage of electricity therethrough, it is understood that this coil 6 or its equivalent may be externally heated, as for example by the association therewith of a separate heating element, as shown in Fig. 10. Here a flexible wire 40 is welded or otherwise readily fastened at 41 to the legs 3 and 4 of the U, these legs being held in the full line position by the wire 40 against the natural tendency of the legs to spring relatively to each other, the coil 6 having terminals

6', as illustrated, for externally heating the wire 40 to cause the expansion of the same. If desired, a sleeve of insulated material 42 may be disposed between the coil 6 and the expandible wire 40. It is understood that the heating coil 6 is suitably connected in circuit to effect either the slow acting switch of Figs. 1 to 3 or to effect the snap action switch of Figs. 4 to 7, or any other circuit may be utilized for causing the control strip 12 to control the contacts or circuit desired. In this modification the U instead of being mounted at the single point on the end of the leg 4 is mounted upon the base or frame support at 45 being a point intermediate the cross piece bridging the legs 3 and 4. Here, as in Figs. 1 and 2, the whole unit is carried at a single point whereby the unit is rendered immune to external disturbing forces and effects.

Fig. 9 shows the mounting of a thermal switch, such as shown in Fig. 2, at a single point 45 intermediate the legs 3 and 4 as shown in Fig. 10.

In Fig. 11 the U comprising the legs 3 and 4 is also mounted at a single point intermediate the legs 3 and 4 as indicated in Figs. 9 and 10. Instead of the heating resistance coils 6 bound around the legs 3 and 4 of the U a single expandible tension wire 50 is fastened at either end to the legs 3 and 4 to hold them in a position to bow or buckle the strip 12. The wire 50 is electrically and mechanically fastened at one end to the leg 4 as indicated at 51. It is electrically insulated from the leg 3 but mechanically fastened thereto by means of a glass bead 52 fused about the wire and disposed in an eyelet 53 conveniently formed in the leg 3 of the U. The wire 50 upon expansion by connecting the same in circuit and heating the same permits the legs 3 and 4 to spring apart under their resiliency and upon cooling to control the contact strip 12. The strip 12 of Figs. 9, 10 and 11 is indicated of uniform strength throughout, but it may be of the character shown in Fig. 8. The device of Fig. 11 may be utilized to control any circuit, as for example any of the above circuits shown in Figs. 3 to 6.

Figs. 1 and 2 indicate the compactness of the whole device by comparison of the size of the terminals with the thermal mechanism itself. The single point of mounting of the mechanism on a frame or support renders, as described above, the whole mechanism substantially free of external disturbance and, accordingly, when the mechanism is once adjusted it operates indefinitely with accuracy at all times. It may be economically manufactured on a quantity production basis and its simplicity in mechanism, parts and operation is obvious. The leg 4 in the modification shown being fixed, the only moving parts of the mechanism are the leg 3 and the strip 12 which simplifies the construction and operation of the switch. The strip or vane 12 is in continuous restraint and is rigidly fastened at both ends to the supporting leg 4 and the relatively moving leg 3 and this construction also assists in rendering the mechanism less subject to outside shocks and influence. In the preferred embodiment the contact 13 and its support 15 are carried by the U member, but it may in certain cases be mounted directly upon the base 1.

In Fig. 7 the relative movements of the members 3 and 4 is exaggerated for convenience in illustration. In actual practice the relative movement of these leg members 3 and 4 is extremely small, but this small movement results in an amplified lateral movement of the inter-

mediate part of the strip 30. For example, I have been able to obtain an amplification of from 1 to 15 to 1 to 25, the possible amplification being greater with the strip constrained as in Figs. 4 to 5 to assume the reverse curvatures at the different points of the length thereof. As an indication of the sensitiveness of the mechanism I have been able to produce automatic snap switch action of the strip 30 with a heating current as 10 low as 2 milliamperes.

I claim:

1. A thermal switch of the character set forth comprising a frame support, a U-resilient spring member, a multiple turn resistance coil bound 15 about the legs of said U-member and causing the same to assume positions against the inherent resiliency thereof, a control strip rigidly fixed to the legs of the U, and a contact mounted upon said U-member and cooperating with said strip, 20 said U-member being mounted upon and fastened at a single fixed point to said frame.

2. In a thermal switch of the character set forth a frame support, a U-resilient spring member, an electrically heated expansible wire fastened to the legs of the U-member and holding the same against their springing outwardly under their inherent resiliency, a controlled strip rigidly fixed at its ends to the legs of the U and flexed so as to assume a curved form and a contact mounted upon said U-member and cooperating with said strip, said U-member being mounted upon and fastened at a single fixed point of support to said frame.

3. In a device of the character set forth, a main support and a thermal electric switch control mechanism mounted thereon, said mechanism comprising a frame support member, and a thermal responsive device and a pair of switch contacts controlled thereby, said contacts and said 35 device being mounted directly upon said frame support member, and said mechanism including the frame support member being fastened to and mounted upon said main support at a single point of support.

4. A thermal control switch of the character set forth comprising a U-resilient spring member, an electrically heated expansible wire fastened to the legs of said U-member and restraining the outward movement of the legs against the natural 45 resiliency thereof, and a circuit control strip bridging and rigidly fastened to the legs of the U, said strip being constrained to assume a curved 50

form with the portions adjacent the ends thereof bowed transversely of the legs in one direction and the middle portion thereof bowed in the opposite direction, and stops disposed on the opposite sides of the middle portion of the strip to limit the movement thereof.

5. A thermal switch of the character set forth comprising a U-resilient spring member, an electrically heated expansible wire fastened to the legs of said U-member and restraining the outward movement thereof against the natural inherent resiliency and a controlled strip bridging and rigidly fastened to the legs of the U, said strip being constrained to assume a curved form with a portion thereof bowed in one direction laterally of the legs and another portion thereof bowed in the opposite direction laterally of the legs, and stops disposed in the path of one of said bowed portions of the strip to limit the movement thereof.

6. In a thermal switch of the character set forth in claim 1 wherein the U-member is mounted and supported upon the supporting frame by means of one of the legs.

7. In a thermal switch of the character set forth in claim 1 wherein the contact is carried by one of the legs of the U.

8. In a thermal switch of the character set forth, a frame support, a U shaped resilient spring member, an electrically heated expansible wire fastened to the legs of the U member and holding the same against their springing outwardly relatively to each other under their inherent resiliency, a controlled strip rigidly fastened at its ends to the legs of the U and flexed so as to assume a curved form, said U member being mounted upon and fastened at a single fixed point of support to said frame and a contact co-operating with said strip.

9. In a thermal switch of the character set forth, a support having at least one resilient spring member, an electrically heated expansible wire rigidly fastened at both ends to said support, one end of the resilient member and holding the same against its springing outwardly relatively to the other part of the support, a controlled strip also rigidly fastened at both ends to the support, one end being fastened to the resilient member and the strip being flexed so as to assume a curved form and a contact co-operating with said strip for controlling an electrical circuit.

JOSEPH SCHMIDINGER.

CERTIFICATE OF CORRECTION.

Patent No. 2,177,671.

October 31, 1939.

JOSEPH SCHMIDINGER.

It is hereby certified that error appears in the printed specification of the above numbered patent requiring correction as follows: Page 4, second column, line 44, claim 9, for the word "of" read --to--; and that the said Letters Patent should be read with this correction therein that the same may conform to the record of the case in the Patent Office.

Signed and sealed this 14th day of May, A. D. 1940.
